SMOKING PIPE

Carroll M. Breed, Orlando, Fla.

Application March 6, 1950, Serial No. 147,797

3 Claims. (Cl. 131—203)

1

It is an object of this invention to provide a smoking pipe with a moisture collecting chamber in the form of a bore extending from the lower end of the bowl to the inner end of the pipe body and having the inner end closed by the stem for the pipe. The moisture collecting chamber may contain a suitable absorbent material in the form of a cartridge capable of being readily inserted into and removed from the inner end of the chamber or bore.

It is another feature of this invention to provide a fitting readily attachable to the body of a smoking pipe and having a moisture collecting chamber communicating with the pipe bowl. According to the present invention the fitting is formed of a material which readily conforms to the contour of the part of the body engaged thereby and is removably secured in place by a resilient band adapted to encircle the pipe body adjacent the bowl.

It is still another object of this invention to provide a smoking pipe with means which assures a free and easy draw, regardless of the compact nature of the tobacco in the pipe bowl. This feature as well as the foregoing and other objects will be made more apparent as this description proceeds, especially when considered in connection with the accompanying drawing, wherein:

Figure 1 is a sectional view through a smoking pipe;

Figure 2 is a sectional view taken on the line 2—2 of Figure 1;

Figure 3 is a cross sectional view taken on the line 3—3 of Figure 1;

Figure 4 is a sectional view through a modified construction of smoking pipe;

Figure 5 is a fragmentary elevational view of a part of the pipe shown in Figure 4;

Figures 6, 7 and 8 are respectively sectional views taken on the lines 6—6, 7—7 and 8—8 of Figure 4.

Referring first to the embodiment of the invention shown in Figures 1 to 3 inclusive, it will be noted that the numeral 10 designates a smoking pipe comprising a body 11 and a stem 12. The body 11 has a bowl 13 and a shank 13' projecting from the bowl. The bowl 13 has a compartment 14 for smoking tobacco and has a moisture collecting recess 15 positioned below the compartment 14. The tobacco compartment 14 is separated from the recess 15 by a partition in the form of a metal disc 16 supported within the bowl 13 on an annular shoulder 17.

2

As shown particularly in Figure 1 of the drawing, a vertical tube 18 is supported in the bowl with the lower end seated on the bottom of the recess 15 and with the upper end projecting through a central opening formed in the partition or plate 16. In the present instance the tube 18 is secured in place by a stud 19 projecting upwardly through an opening in the bottom of the bowl and threadably engaging the lower end portion of the tube 18. The upper end of the tube 18 is closed by a disc 20 having a diameter somewhat less than the internal diameter of the tobacco compartment 14 and having the peripheral portion 21 flared in a downward direction toward the partition 16.

Referring again to Figure 1 of the drawing, it will be noted that the closure disc 20 is spaced above the partition 16 and the side wall of the tube 18 immediately below the disc 20 is formed with a series of ports 22. The purpose of the ports 22 is to permit relatively free passage of smoke from the compartment 14 into the tube, and the purpose of the disc 20 is to shield the ports 22 against obstruction by tobacco when the latter is packed into the compartment 14.

The tube 18 communicates intermediate the ends thereof with a smoke passage 23 which extends from the tube 18 to the free end of the shank 13' on the body 11. In detail a tube 24 is secured within a bore formed in the shank 13' of the body 11. The outer end of the tube 24 projects into the recess 15 and through an opening formed in the adjacent wall of the vertical tube 18. The inner end of the tube 24 communicates with a counterbored recess 25 formed at the inner end of the bore in the shank 13'.

A port 26 is formed in the bottom of the tube 24 adjacent the vertical tube 18 to drain moisture from the smoke passage or tube 24 into the recess 15 of the pipe bowl 13. In the present instance the moisture is collected by a cartridge 27 of absorbent material housed in a bore 28 formed in the body 11 adjacent the bottom of the latter. The outer end of the bore opens into the recess 15, and the inner end of the bore opens through the adjacent end of the body 11. The construction is such as to permit the absorbent cartridge 27 to be readily inserted into and removed from the bore 28 through the open inner end of the latter. It will be observed from Figure 1 that the outer end of the cartridge projects into the recess 15 and is positioned directly below the drainage port 26 to receive moisture from the latter.

The stem 12 has a smoke passage 29 there-

through adapted to register with the smoke passage 23, and a metal tube 30 is secured in the passage 29. The tube 30 is of a diameter less than the internal diameter of the tube 24 and is adapted to telescope into the tube 24 when the stem is attached to the body 11. The outer end of the stem is enlarged and corresponds in shape to the adjacent inner end of the pipe body 11. As shown in Figure 1 of the drawing, the outer end of the stem has two projections 31 and 32. The projection 31 is of a size to fit into the counterbore 25, and the projection 32 fits into the inner end of the bore 28 to close the latter.

Referring now to the embodiment of the invention shown in Figures 4 to 8 inclusive, it will be noted that the numeral 35 designates a fitting which is readily attachable to a smoking pipe of conventional shape. In general the smoking pipe has the usual body part 36 and stem part 37. The outer end of the body part is shaped to form a bowl 38, and the inner end is counterbored to receive the outer end of the stem 37.

In the present instance the bowl 38 has a tobacco compartment 39 and a recess 40 located below the compartment 39. The recess 40 is separated from the tobacco compartment 39 by a plate 41 having the peripheral portion seated on an annular shoulder formed in the bowl, and having the central portion depressed or formed to provide a depending tubular section 42. The tubular section 42 is reduced to form a vertical tube 43, and to provide an annular shoulder 44. The lower end of the tubular section 43 engages the bottom of the recess 40, and communicates with an opening 45 formed in the bottom of the bowl 38. Sleeved within the tubular part 42 is a tube 46. The lower end of the tube 46 is seated on the lower end of the shoulder 44 and upper end of the tube projects above the partition 41. A disc 47 closes the upper end of the tube 46, and the peripheral portion of the disc projects beyond the side wall of the tube.

A series of ports 48 are formed in the side wall of the tube 46 adjacent the upper end of the latter in a position to be protected against obstruction by the closure disc 47. The ports 48 permit free passage of smoke from the compartment 39 into the recess 40 through outlet openings 49 formed in the side wall of the tubular section 43. The smoke discharged into the recess 40 through the openings 49 enters a smoke passage 50 formed in the pipe body which extends from the recess to the smoke passage 51 in the stem 37.

The fitting 35 is readily conformable to the contour of the portions of the pipe engaged thereby, and in the present instance is shown as molded from a resilient material, such as rubber or synthetic rubber. It will be noted from Figure 4 that the fitting snugly engages the pipe body 36 and the stem 37 at the undersides of the latter, and is held in place by a strap 53 formed integral with the fitting and adapted to slip over the stem to enable positioning the same around the body 36 of the pipe adjacent the bowl 38.

The fitting 35 has a recess 54 which cooperates with the underside of the pipe body 36 to form a moisture collecting chamber 55. This chamber communicates with the interior of the recess 40 in the pipe bowl through the opening 45, and preferably contains a cartridge 56 of absorbent material. Thus the moisture drained from the bowl of the pipe is absorbed in the cartridge 56 and the latter may be replaced by merely detaching the fitting 35 from the pipe body.

It follows from the above that the fitting 35 may be readily attached to conventional smoking pipes with a minimum alteration of the pipe structure. In fact the only modification required is to drill or otherwise form the opening 45 in the bottom of the pipe bowl. The partition 41 and associated tubing is not essential for satisfactory use of the fitting, and accordingly, may be omitted if desired.

What I claim as my invention is:

1. A smoking pipe comprising a body having an upwardly opening bowl, a partition in the bowl providing a tobacco compartment at the top of the bowl and a moisture collecting recess at the bottom of the bowl, said body having a smoke passage, a vertical tube in the bowl extending upwardly through the partition, said tube having the upper end closed and having a port in the side wall spaced above the partition for the passage of smoke, an outlet tube connected to the vertical tube intermediate the ends thereof and to the smoke passage and having an opening located to drain moisture from the outlet tube into the moisture collecting recess, and a stem attachable to the inner end of the body and having a passage registering with the smoke passage in the body.

2. The smoking pipe set forth in claim 1 in which said body has a bore containing absorbent material which extends from the inner end of the body and opens into the moisture collecting recess adjacent the bottom of the latter, and in which pipe the inner end of the bore is closed by the stem.

3. A smoking pipe comprising a body having an upwardly opening bowl, a partition in the bowl providing a tobacco compartment at the top of the bowl and a moisture collecting recess at the bottom of the bowl, said body having a smoke passage, a vertical tube in the bowl extending upwardly through the partition, said tube having the upper end closed and having a port in the side wall spaced above the partition for the passage of smoke, an outlet tube connected to the vertical tube intermediate the ends thereof and to the smoke passage and having an opening located to drain moisture from the outlet tube into the recess, a bore in the body below the smoke passage and extending from the inner end of the body to the recess, an absorbent material housed in the bore for collecting moisture draining into the recess, and a stem attachable to the inner end of the body and having a projection engageable in the adjacent end of the bore.

CARROLL M. BREED.
